UNITED STATES PATENT OFFICE

2,428,514

WELT TURNING MECHANISM IN STRAIGHT BAR KNITTING MACHINES

William Arthur Cooper and William Gordon Macdonald, Loughborough, England, assignors to William Cotton Limited, Loughborough, England

Application April 18, 1946, Serial No. 663,114
In Great Britain January 6, 1945

Section 1, Public Law 690, August 8, 1946.

5 Claims. (Cl. 66—96)

1
This invention comprises improvements in and relating to welt turning mechanism of Cotton's patent and other straight bar knitting machines, especially machines specifically intended for the manufacture of the blanks for ladies' fully fashioned stockings. It concerns welt-turning mechanism of the kind wherein welting instruments (or welt hooks) are inserted from the plain side of the needles to receive thread or thread kinks of an initial welt course, are retracted from the needles during the knitting of at least a portion of the welt, are subsequently advanced to offer the initial welt course held by them to be transfixed by rising needles; and are disengaged from the transfixed course by retraction.

Mechanism of this kind is described in British patent specifications Nos. 548,874, 537,336 and 537,368.

The difficulty arises that at or near the selvedges the instruments do not always retract clear of the yarn of the initial course and the loops thereof are broken. It is thought that this is due to a tendency of the rising needles to tilt up the welt bar and to carry the hooked portions of the welting instruments into or nearly into the sinkers with the result that, since the fabric is more bulky near the selvedges owing to rolling over, there is not sufficient clearance for the hooked portions to miss all the loops in their retractive movement. It is an object of the invention to provide a construction in which the aforesaid difficulty is obviated or minimised.

According to this invention welt-turning mechanism of the kind referred to is characterised by supports for engaging the initial course at least in the neighborhood of the selvedges and means for lifting said supports in relation to the welting instruments to facilitate the retraction of the latter from the transfixed initial course. These supports may be constituted by instruments that register with and move upwards with the needles, and the said support instruments may also function to deflect spaced needles out of alignment to ensure an efficient transfer.

The foregoing and other features of the invention, set out in the appended claims, are incorporated in a construction, which will now be described with reference to the accompanying drawings in which—

Figures 1a and 1b show a cross section through the knitting machines showing the relevant parts thereof;

Figure 2 is an elevation of the knocking-over bar and associated parts;

2
Figure 3 is an end view thereof, partly in section;

Figures 4 and 5 show portions of the mechanism for operating the support instruments;

Figure 6 is an elevation on a larger scale of one of the support instruments aforesaid and

Figure 7 is a section on a still larger scale through the head thereof, while

Figures 8-12 inclusive are diagrams illustrating the operation of said instruments.

The said construction is described as an example of the application of the invention to a welt-turning mechanism functioning substantially as described in patent specifications Nos. 537,336

15 and 537,368 (to which reference is to be made) and having a welt hook for every needle space. Figures 1a and 1b show the relevant parts of the machine, including needle bar 1 with bearded needles 2, sinker head 3 and pressing edge 4, sinkers 5, knock-over bits 6, carriers 7, welt bar 8, mounted on guides 9, (operable by mechanism

20 which, since it is described in any of the aforesaid patent specifications, requires no description or illustration herein) and carrying the welt

25 hooks 10, and main cam shaft 11 carrying cams from which the knitting and welt-turning motions are derived. The needle motions are conventional: the vertical movements are communicated by rock shaft 12 and truck lever 13 and the pressing motions are communicated by truck

30 lever 14, rockshaft 15, and hand lever 16. The sinker movements are also conventional and are derived from slur-cock 17 and catch bar 18, both operated in known manner. The knock-over bar

35 28 is supported on rock shaft 21 which is rocked by truck lever 22, and cam 27. Shaft 21 is supported by arms 23 from shaft 24 which is rocked by truck lever 25 and cam 26.

Associated with every second needle there is 40 an auxiliary presser 19 which pressers are mounted below the knocking-over bits 6 and extend up between them. They are carried by bar 20 which is mounted on the front of the knock-over bar

28, but are capable of up and down movement

45 independently of the latter. For this purpose the bar 20 is slidably mounted at 29 and is drawn downwards by springs 30, Fig. 2, being raised by rockers 31 operable by a bar 32 slidably horizontally

50 along the machine frame member 33. Bar 32 is movable by the mechanism shown in Figs. 4 and 5, from a cam 34 on the main cam shaft 11 operating a truck-lever 35. The latter is connected to a vertically movable cam slide 36 by a connecting rod 37 and hinged joints 38, 39 and

55 the cam slide has two parallel, inclined faces 36a

3

which are received between like faces 32a on bar 32. Therefore, when the cam slide is lowered from its Fig. 5 position, bar 32 is forced to the left and when it is raised again the bar is forced to the right.

At the commencement of the welt the pressers 19 are operated to press off every second needle instead of the points 21 of the said specification so that (there being a welt-hook 10 for every needle space) between every other needle the kink pressed off from the intervening needle extends over two welt hooks; at the finish of the welt they are operated to deflect every second needle towards the front of the machine (out of alignment with the other needles) so that when each said second needle rises it will penetrate with more certainty a thread loop or kink of the initial welt course, which loop or kink was initially pressed off from it and extends across a pair of welt hooks 10.

As shown in Figs. 6, each of these pressers 19 comprises a flat head 19a, to pass up between the sinkers, having its straight front edge formed with a groove 19b to receive or cover the needle beard, and at least the pressers associated with the selvedge needles and preferably all pressers are cut back from said edge at the top of the head to form support shoulders 19c.

Turning now to Figs. 8-12, Fig. 8 illustrates the phase in the welt-turning operations whereat the welt fabric F has been knitted and is pulled by the inserted welt rods or wires (not shown) in a bight beneath the welt bar so that the initial kinks are supported on the elevated ledges of the welt instruments 10 as described in the specifications referred to.

In the operation of restoring the initial course to the needles 2 the welt bar 8 advances and the welt hooks 10 are inserted horizontally below the sinkers 5 and above the knocking-over bits 6 while the needles 2 and auxiliary pressers 19 are lowered, Fig. 9. The latter then move forward (Fig. 10) to press the beard of every second needle 2 and to deflect said needles out of alignment with the other needles. Needles 2 and pressers 19 then rise together (Figs. 10 and 11) so that the deflected needles enter the thread kinks held over the support ledges of the welt hooks 10 and said thread kinks lodge on the support shoulders 19c of the pressers. This movement carries the thread kinks well up into the sinkers 5 and permits the welt hooks to be disengaged by a sharp retiring movement (Fig. 12) the needles 2 continue to ascend and the pressers 19 are lowered.

Thus the initial welt course has been restored to the needles so that the next course is drawn through the initial course and the latter is thereby secured.

We claim:

1. In a Cotton's patent or other straight bar knitting machine having welt-turning mechanism wherein welting instruments, one for each needle space, are inserted from the plain side of

the needles to receive thread kinks of an initial welt course cast off from every second needle, are retracted from the needles during the knitting of at least a portion of the welt, are subsequently advanced to offer the initial welt course kinks held by them to be transfixed by every second needle in rising, and are disengaged from the transfixing course by retraction, the combination of an auxiliary presser for every second needle, means for operating said pressers at the commencement of the welt, to press every second needle to cast off its thread kink of the initial welt course, means for operating them at the termination of the welt to deflect each second needle towards the plain side of the needle line to transfix the kinks offered by the welting instruments, and means for raising said pressers to lift the transfixing kinks for the retraction thereof from the welting instruments.

2. Mechanism according to claim 1, wherein each auxiliary presser has a ledge for supporting the thread kink and a groove for receiving the needle beard.

3. In a straight bar knitting machine having welt turning mechanism of the kind wherein welting instruments, one for each needle space, are inserted from the plain side of the needles to receive thread kinks of an initial welt course cast off from spaced needles, are retracted from the needles during the knitting of at least a portion of the welt, are subsequently advanced to offer the initial welt course kinks held by them to be transfixed by spaced needles in rising, and are then disengaged from the transfixing course by retraction; the combination of supports for engaging kinks of the initial welt course at least in the neighborhood of the selvedge, and means for lifting said supports in relation to the welting instruments to facilitate the retraction of the latter from the transfixing kinks.

4. Mechanism according to claim 3 being of the kind wherein, at the commencement of the welt, kinks of the initial course are pressed off or cast off spaced needles and are returned to said spaced needles at the termination of the welt, having a support for each of said spaced needles.

5. Mechanism according to claim 3, having a support for each of spaced needles and means for operating said supports to press spaced needles at the commencement of the welt in casting off thread kinks of the initial welt course from said spaced needles.

WILLIAM ARTHUR COOPER.
WILLIAM GORDON MACDONALD.
